United States Patent Office.

S. J. BRIDGE AND A. M. CRAIG, OF PORTAGE CITY, WISCONSIN.

Letters Patent No. 62,929, dated March 19, 1867.

IMPROVEMENT IN WATER-WHEELS.

The Schedule referred to in these Letters Patent and making part of the same.

TO ALL WHOM IT MAY CONCERN:

Be it known that we, S. J. BRIDGE, and A. M. CRAIG, of Portage City, in the county of Columbia, and State of Wisconsin, have invented certain new and useful improvements in Water-Wheels; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention consists in constructing a wheel, with a series of deflecting guides on its upper surface, and having a series of spiral buckets arranged at its periphery, with an air chamber in its central portion underneath.

Figure 1 is a top plan view of the wheel and case, with the top of the latter removed.

Figure 2 is a transverse vertical section to turn on the line $x x$ of fig. 1.

In making our wheel, we provide a circular plate or disk H, with a central hub, B, and attach it to the shaft C, as shown in figs. 1 and 2. To the outer edge of this plate H is secured a vertical flange G, projecting downward at a right angle, as shown in fig. 2; and outside of this is placed, at some distance, another similar rim or flange, D, which forms the outer edge of the wheel. The space between these two vertical rims G and D is occupied by a series of buckets b, which consist of a metal plate bent in a spiral form, so as to form a gradually descending curve from the top to the bottom of the rims, in the direction indicated by the red arrows in fig. 1. Upon the upper surface of the plate H is arranged a series of guides or strips, a, as shown in fig. 1, the inner portion of said guides being arranged tangentially around the hub B, as far out as the rim G, from whence they extend radially to the outer rim D, this outer portion of the guide-strips a forming the division between the buckets, there being as many of the guide-strips as there are of the buckets. By this method of constructing the wheel, it will be observed that there is formed in the central portion of the wheel, under the plate H, an air chamber or space E, as shown clearly in fig. 1, and when the wheel is properly set, with its upper surface nearly level with the water in the pit or tail-race, it will be seen that the air in this chamber will render the wheel somewhat buoyant, and thus tend to counteract the downward pressure of the water above. The wheel is placed in a scroll-case with its upper surface nearly even with the bottom of the case, as shown in fig. 2. The water entering the mouth of the scroll, impinges against the guides a, directly, thereby imparting more or less motion to the wheel. At the same time, the inclined position of the guides deflects the water to the outer portion of the wheel, where it passes down between the buckets b, reacting on them, and escaping at the bottom in a direction the reverse of that at which it entered. By these means we are enabled to produce a very cheap and simple wheel, and one in which the power or force of the water is utilized in a very efficient manner. It is obvious that the wheel may be constructed entirely of wood or of metal, or of both combined, as may be found most convenient.

Having thus described our invention, what we claim is—

A water-wheel having the spiral buckets b, and the tangential guides a, combined and arranged substantially as shown and described.

S. J. BRIDGE,
ALLEN M. CRAIG.
